(57) **CLAIM**

The ornamental design for a welding machine for plastic sheets, as shown and described.

DESCRIPTION

FIG. 1 is a front perspective view of a welding machine for plastic sheets showing our design;

FIG. 2 is a left side elevational view thereof;

FIG. 3 is a right side elevational view thereof;

FIG. 4 is a front elevational view thereof;

FIG. 5 is a rear elevational view thereof; and,

FIG. 6 is a top plan view thereof.

1 Claim, 3 Drawing Sheets

FIG. 1**FIG. 2**

FIG. 3**FIG. 4****FIG. 5**

FIG. 6
